SAFETY DEVICE FOR PROJECTILES

Edgar William Brandt, Geneva, Switzerland, assignor to Anstalt fur die Entwicklung von Erfindungen und Gewerblichen Anwendungen "Energa," Vaduz, Liechtenstein, a corporation of Liechtenstein

Application April 22, 1952, Serial No. 283,600

1 Claim. (Cl. 102—78)

This invention relates to projectiles of the type comprising a head fuze and a detonator disposed towards the rear of the projectile, and which are provided with a safety and arming-retarding device disposed between said fuze and detonator. Such an arrangement is designed to prevent accidental transmission of fire during transport and handling and to ensure muzzle safety for the projectile.

The safety device of the present invention is of the kind comprising two parts which are movable relatively to one another, one of which parts has at least one groove in which is engaged a sliding member integral with the other part, forming an obturator, and which is operated by a resiliently constrained member, for example, a spring. The moving part of the device serves as a screen in the safety position, and must be dislodged after the shot has been fired, thereby freeing the useful passage for the transmission of fire from the head fuze to the detonator.

The safety device according to the present invention is characterised in that the resiliently constrained thrust member is secured by its front end to the obturator and is provided at its rear end with a valve which, under the action of the thrust member, keeps the internal passage of the safety device closed until the principal obturator is completely released.

The result produced by the aforescribed arrangement is that until the end of the operation of the safety mechanism, the valve ensures perfect obturation, and that, in the event of accidental percussion of the head fuze immediately after firing the shot, the muzzle safety device still functions by virtue of the fact that the valve hereinbefore referred to is forced under the action of the gases liable to pass between the two parts of the device, tightly against its seat.

According to one embodiment of the invention, in order to supplement the action of the safety device, the obturator has on its outer face a group of sealing grooves which, similarly to piston rings, oppose the passage of the gases between the two parts of the device, as long as the latter has not operated.

In order to enable the invention to be more readily understood, reference is made to the accompanying drawings, which illustrate diagrammatically and by way of example, one embodiment thereof and in which:

Fig. 1 illustrates the projectile in partial axial section;

Fig. 2 is an enlarged axial section of the safety device denoted by the reference numeral 1 in Fig. 1; and

Fig. 3 shows the functioning of the safety device shown in Fig. 2.

As shown in Fig. 1, the safety device 1 of the present invention is interposed, in a hollow-charge grenade 2, between a head fuze 3 and a detonator 4, the latter hav-

2

ing the function of communicating the fire to a relay charge 5, which explodes the high explosive charge 6, the metal cap 7 of which lines the cavity 8.

Figures 2 and 3 show details of the construction of the safety device having, in a casing 1a a hollow inertia device or obturator 9, which carries two slides 10 each of which engages in a zig-zag groove 11 provided in the support 12.

An ejection spring 13 holds the inertia member 9 bearing against the slide 10 at the bottom of the blind part 11b of the groove 11 (Figure 3). In this position, the obturator 9 prevents transmission of fire from the primer 14 to the detonator 4.

The spring 13 is secured at its front end to a nipple 15 firmly fitted in the solid head of the obturator 9, and a small seal 16 is fixed to the rear end of the spring 13, so that in the safety position, the seal 16 bears against a circular seating 17 formed in the base of the support 12 and thus reinforces the obturation provided by the inertia member 9.

In order to ensure perfect tightness of the safety device, the inertia member 9 is provided on its outer face with a series of grooves 18 which imposes a baffled path on any accidental transmission of fire.

On firing the shot, the inertia member 9 under the influence of the propulsive action, while following the movement imposed on it by the blind part 11b of the groove, compresses the thrust member or spring 13 by inertia and then, on the cessation of the positive acceleration, the spring 13 pushes the inertia member 9 towards the front and its slides 10 follow respectively the branches 11a of each of the zig-zag grooves. As long as the spring 13 has not been completely slackened, the seal 16 remains in position and continues to close the passage provided in the base of the support 12. The inertia member or obturator 9, when ejected by the spring 13, frees the firing orifice and by falling into the cavity 8 of the projectile, takes up position, together with the attached spring 13 and seal 16, near the primer 14, at 9a (Figure 1). Since the spring 13 is secured to the obturator 9, it accompanies the latter when it is displaced from the cap 8, so that when the explosion occurs the spring is no longer in the field of action of the perforating jet. Experience shows that the penetrating power of the hollow explosive charge is thereby improved.

It is obvious that the invention has only been described by way of example and that various modifications and alterations can be made thereto without departing from the scope thereof as defined by the appended claim.

What I claim is:

A safety and delay device for a projectile fuse, comprising a support with a longitudinally extending passage through which fire is to be transmitted, an annular seat at the rear of said passage, a seal removably held on said seat, an obturator axially movable on the support, and a resilient compression thrust member within the passage and attached at its ends to the seal and to the obturator for projecting the obturator and seal forwardly from the support under the force of inertia.
